DESIGN FOR A THERMOMETER

Clare E. Hodgman, Tuckahoe, N. Y., assignor to
Taylor Instrument Companies, Rochester, N. Y.,
a corporation of New York

Application September 20, 1947, Serial No. 141,515

Term of patent 14 years

(Cl. D52—7)

To all whom it may concern:

Be it known that I, Clare E. Hodgman, a citizen of the United States, residing at Tuckahoe, in the county of Westchester and State of New York, have invented a new, original, and ornamental Design for a Thermometer, of which the following is a specification, reference being had to the accompanying drawing, forming part thereof, in which:

Fig. 1 is a front view of a thermometer showing my new design;

Fig. 2 is a side elevation of this thermometer;

Fig. 3 is a vertical section taken on the line 3—3 of Fig. 1;

Fig. 4 is a horizontal section taken on the line 4—4 of Fig. 1; and

Fig. 5 is a rear view on a greatly reduced scale of the thermometer.

I claim:

The ornamental design for a thermometer, as shown.

CLARE E. HODGMAN.
